(57) **CLAIM**

The ornamental design for a piston for driving water out a disrupter, as shown and described.

DESCRIPTION

FIG. 1 is a perspective view of the piston for driving water out a disrupter showing the side and the top;

FIG. 2 is another perspective view of the piston for driving water out a disrupter showing the side and the bottom;

FIG. 3 is a view of the side of the piston for driving water out a disrupter all sides having the same view because the piston is circular;

FIG. 4 is a view of the bottom of the piston for driving water out a disrupter; and,

FIG. 5 is a view of the top of the piston for driving water out a disrupter.

1 Claim, 2 Drawing Sheets
